(57) **CLAIM**

The ornamental design for a beamforming microphone, as shown and described.

DESCRIPTION

FIG. 1 is a perspective view of an beamforming microphone showing the new design;

FIG. 2 is a left side view of the new design;

FIG. 3 is a right side view of the new design;

FIG. 4 is a back view of the new design;

FIG. 5 is a front view of the new design;

FIG. 6 is a top view of the new design; and,

FIG. 7 is a bottom view of the new design.

The broken-line disclosure is understood to represent portions of the article in which the claimed design is embodied, but which form no part of the claimed design.
